[57] CLAIM

The ornamental design for a detachable holder for drink cans, as shown and described.

DESCRIPTION

FIG. 1 is a top perspective view of the detachable holder for drink cans showing my new design, the broken line showing of the second detachable holder and cans is for illustrative purposes only and forms no part of the claimed design;

FIG. 2 is a top plan view;

FIG. 3 is a side view, the right, left, top, and bottom all being identical;

FIG. 4 is a perspective bottom view;

FIG. 5 is a cross-sectional view taken on line 5—5 of FIG. 2; and,

FIG. 6 is a side and bottom perspective view of a second embodiment of FIG. 1, the remaining sides being identical.

The top view of the second embodiment is identical to the first embodiment.
